US00D349488S

United States Patent [19]

Aderman et al.

[11] Patent Number: Des. 349,488

[45] Date of Patent: ** Aug. 9, 1994

[54] **DISK STORAGE SUBSYSTEM FOR A DATA PROCESSING SYSTEM**

[75] Inventors: **Wayne L. Aderman**, Zumbro Falls; **David W. Hill**, Rochester, both of Minn.

[73] Assignee: **International Business Machines Corporation**, Armonk, N.Y.

[**] Term: **14 Years**

[21] Appl. No.: **834,500**

[22] Filed: **Feb. 11, 1992**

[52] U.S. Cl. **D14/109**

[58] Field of Search 360/99.12; 361/390-395; D14/100, 102, 108, 109; D13/162, 184, 199

[57] **CLAIM**

The ornamental design for a disk storage subsystem for a data processing system, as shown and described.

DESCRIPTION

FIG. 1 is a reduced top front and left side isometric view of a disk storage subsystem for a data processing system showing our new design;

FIG. 2 is a front elevation thereof;

FIG. 3 is a right side elevation thereof;

FIG. 4 is a rear elevation thereof;

FIG. 5 is a top plan thereof;

FIG. 6 is a bottom plan thereof; and,

FIG. 7 is an enlarged partial front elevation of the control panel thereof shown separately for clarity of illustration only.

FIG. 1

FIG. 2

FIG. 7

FIG. 3

FIG. 4

FIG. 5

FIG. 6
